UNITED STATES PATENT OFFICE.

JAMES H. LA PEARL, OF CHICAGO, ILLINOIS.

MOVABLE ADVERTISING-SIGN.

No. 922,784.

Specification of Letters Patent.

Patented May 25, 1909.

Application filed April 7, 1908. Serial No. 425,665.

To all whom it may concern:

Be it known that I, JAMES H. LA PEARL, a citizen of the United States, residing at Chicago, in the county of Cook and State of Illinois, have invented certain new and useful Improvements in Movable Advertising-Signs, of which the following is a specification.

This invention relates to signs intended for advertising purposes; and the object of the invention is to so construct and arrange the sign as a whole that several advertisements may be intermittently displayed, thereby increasing the effectiveness of the display in proportion to the space occupied by the device, whereby three signs can be arranged to occupy substantially the same space that is ordinarily allotted to one. The display panels, furthermore, are mounted to revolve so that different signs will be successively displayed, and such movement serves to attract attention to the sign and arrest the notice of passersby.

The invention further relates to the construction and arrangement of the display panels and to the means provided for actuating the same, and to the device as a whole and the individual parts thereof.

The invention consists in the features of construction and combination of parts hereinafter described and claimed.

In the drawings, Figure 1 is a front elevation of the sign box, showing one of the panels partially broken away; Fig. 2 a side elevation of the same, showing the panels in a different position of adjustment; Fig. 3 an enlarged detail of the bracket arm for actuating the rack bar; Fig. 4 a sectional view of the same; and Fig. 5 a perspective view of one of the panels very much enlarged.

The sign as a whole comprises a rectangular box having side walls 6, a top 7, and a back 8, the front of the box being open. The box may be made of a size to adapt the sign for window display, or may be made sufficiently large to serve in the capacity of a billboard. Furthermore, the shape and proportions of the box may be changed or modified to suit the requirements of the space intended to be occupied by the sign. The box is preferably provided near its bottom 9 with a shelf or partition wall 10 which divides the box into an enlarged upper or display portion 11 and a smaller lower portion 12, which latter furnishes a chamber or receptacle for the actuating mechanism. Within the dis-

play portion of the box are located a plurality of panels 13 of any suitable number, three being shown in the drawings for purposes of illustration. The panels are of a size to completely fill the display portion of the side box when turned edge to edge, and are each provided at the ends with trunnions 14 and 15, which trunnions are journaled through the side walls of the box and permit the panels to be revolved. The trunnions 15 have located thereon pinions 16 which mesh with rack teeth 17 carried by a rack bar 18 which is adapted to receive a reciprocating motion sufficient in degree to impart to the panels a half revolution with each stroke of the rack bar, which half revolution serves to display the reverse side of the panels so that each side will be alternately displayed. The opposite faces of the panels serve for the display of suitable advertising matter and, in the form shown, as is desirable in the displaying of large and important advertisements, a single advertisement is painted or inscribed on the entire surface afforded by the full number of panels, so that when the latter are turned edge to edge and the proper surfaces fully exposed the advertisement thereon will appear for a limited time on a flat unbroken surface. The opposite sides of the panels being likewise inscribed, two full and complete advertisements can be displayed on the panels themselves. In order to increase the capacity of the sign, the front face of the back or inner wall of the box is likewise provided with a sign which will be fully exposed when the panels are turned into edgewise position, as shown in Fig. 2, so that in effect three complete signs can be displayed in substantially the same space ordinarily occupied by a single sign.

It is desirable, in the operation of the panels, that their movements should be momentarily arrested when they have been turned edge to edge, and likewise when they have been turned to their intermediate position, in order that the signs displayed on opposite sides of the panels may be fully exposed for a suitable period of time and likewise the sign displayed on the inner wall of the box itself. Suitable mechanism for providing an intermittent movement of the character indicated is shown in Figs. 3 and 4. The rack bar 18 is provided, near its end, with an inwardly extending rack arm 19 which is preferably provided, at its end, with

a slot 20 through which is entered a thumb nut 21 which permits adjustment of the arm upon the bar. The arm, at its inner end, is provided with a head 22 having therein a slot 23 narrow at the center and enlarged at each end, which slot affords inwardly converging contact surfaces 24 which are adapted to be engaged by a crank pin 25 on a crank arm 26, which arm is adapted to be revolved by a suitable motor 27 of any desired character. The crank pin 25 is adapted to travel within the outwardly diverging slot 23 and bear against the contact walls thereof. The slotted head 22 is further provided with inwardly extending tongues 28 and 29 which are pivoted at opposite ends of the slot and are adapted to bear against the upper and lower walls of such slot, as shown in Fig. 3, with the result that when the crank pin is moved to a position to bear against the inner or free face of one of the tongues said tongue will bear against the adjacent surface 24, thereby moving the slotted arm in a straight line to accommodate the revolving movement of the crank pin, and this movement will continue until the crank pin has swung to a position in alinement with a slot or recess 30 near the pivoted end of each of the tongues, through which slot or recess the crank pin is adapted to swing. On the return movement of the crank pin, the tongue will be free to swing away from the surface against which it normally rests, thereby allowing the unimpeded movement of the pin. Fig. 3 shows in full lines and dotted lines two of the positions occupied by the crank pin and slotted arm. With the crank arm in its uppermost position and moving in the direction of the arrow, the crank pin will swing over into contact with the tongue 29 and will maintain such contact and thereby force down the slotted arm continuously until the pin reaches a position where it will pass through the slot 30 at the inner end of the tongue, in which position, as shown in dotted lines, it will travel for an eighth of a revolution without engaging the walls of the slotted arm, thereby allowing the slotted arm to remain stationary until the pin again comes in engagement with the bottom of the slot, after which the slotted arm will be subjected to an additional movement until the lower apex at the contracted or central portion of the slot is reached by the crank pin, at which time the pin will pass under the inner or free end of the tongue 29 and the arm will remain stationary until the pin engages the under face of the tongue 28, after which the slotted arm will be raised by the interrupted movement similar to that previously described. The position of the pin with respect to the arm is such that the periods of rest will occur when the panels are brought into register with either face out and also when the panels are thrown into the position shown in Fig. 2.

and their edges only exposed to the observer's eye. In this manner each of the signs will be fully exposed to the observer's eye without movement for a sufficient length of time to permit the sign as a whole to be read and understood, after which the movement will again commence and the signs be shifted.

Fig. 5 shows a panel provided with face plates 31 which are preferably in the form of thin metal plates having a picture or sign painted, printed, or otherwise applied thereon, which plates are secured to the faces of the panel proper by being slid into clips or brackets 32 and held in place, when inserted, by means of a pivoted spring clip 33 having fingers 34 adapted to engage the edges of the face plates and adapted to be sprung back into the position shown in dotted lines. The spring clip co-operates with pins or studs 35 which outwardly project through holes 36 in the face plates, which pins or studs serve to sustain the weight of the plates which are held in engagement therewith by means of the spring clip which, being pivoted, can be raised and moved from side to side to permit the insertion of the plates.

In use the sign box can be displayed from any suitable point of advantage and the number of panels and their size and shape determined with reference to the nature of the advertisement intended. With the parts in the position shown in Fig. 1, when the motor is started, the panels will be continuously turned until they are moved into the position shown in Fig. 2, which position they will occupy for a period sufficiently long to enable observers to read the sign displayed within the box, after which the movement of the rack bar will cause the panels to complete a half revolution in order to display the advertising matter contained on the back of the panel. When such movement is completed the panels will stop for a suitable period and thereafter be moved in a reverse direction, broken by a period of rest, until they have been moved to their initial position.

Of course, the sign can be provided, if desired, with such accessory features as electric lights or other well known advertising features. Where panels are provided with removable face plates, the character of the advertisement displayed can be easily changed from time to time, which feature renders the device peculiarly suitable for use in theater advertising and in advertising bargain sales and matters of like nature.

What I regard as new and desire to secure by Letters Patent is:

1. A device of the class described comprising a plurality of reversible panels pivoted at each end in their centers and located adjacent each other and adapted, when in register, to present a continuous surface for the reception of advertising matter and adapted to be reversed to bring their opposite faces

similarly into register, and means located at one side of the bank of panels for reversing the panels, substantially as described.

2. A device of the class described comprising a plurality of substantially rectangular reversible panels located adjacent each other and adapted, when in register, to present a continuous surface for the reception of advertising matter and adapted to be reversed to bring their opposite faces similarly into register, means located at one side of the bank of panels for reversing the panels, a box within which the panels are pivoted, said box being provided with a display surface behind the panels adapted to receive an advertisement, pinions connected with each of the panels, a continuous rack bar at the side of the bank of panels and provided with teeth engaging the pinions, a motor provided with a revoluble crank pin, and an arm connected with the rack bar and having therein a slot into which the crank pin is entered, said slot having a configuration to impart an intermittent movement to the rack bar for maintaining the panels in a state of rest when in position to display the advertising matter on opposite sides thereof and when in a position to fully expose the advertising surface within the box, substantially as described.

3. A device of the class described comprising a plurality of substantially rectangular reversible panels located adjacent each other and adapted, when in register, to present a

continuous surface for the reception of advertising matter and adapted to be reversed to bring their opposite faces similarly into register, a box within which the panels are pivoted, said box being provided with a display surface behind the panels adapted to receive an advertisement, pinions connected with each of the panels, a continuous rack bar at the side of the bank of panels and provided with teeth engaging the pinions, a motor provided with a revoluble crank pin, and an arm connected with the rack bar and having therein a slot into which the crank pin is entered, said slot having a configuration to impart an intermittent movement to the rack bar for maintaining the panels in a state of rest when in position to display the advertising matter on opposite sides thereof and when in a position to fully expose the advertising surface within the box, substantially as described.
